William Padernacht Inventor:

UNITED STATES PATENT OFFICE.

WILLIAM PADERNACHT, OF NEW YORK, N. Y.

ADJUSTABLE COAT.

1,010,679.

Specification of Letters Patent.

Patented Dec. 5, 1911.

Application filed July 7, 1910. Serial No. 570,703.

To all whom it may concern:

Be it known that I, WILLIAM PADERNACHT, a citizen of the United States, and a resident of New York, borough of Manhattan, 5 county and State of New York, have invented certain new and useful Improvements in Adjustable Coats, of which the following is a specification.

This invention relates to ladies' outer garments, particularly coats or jackets, which are adjustable to various sizes within a certain limited range.

The invention more particularly contemplates what may be termed a "maternity coat," certain dimensions of which may be gradually increased from time to time as occasion requires, thereby obviating the necessity for the purchase of an ill-fitting garment, or a number of garments of various 20 sizes, the means for adjusting the coat to fit the changing figure of the wearer being of such a character that the garment always presents a neat and finished appearance in all conditions of adjustment.

My invention will be more readily understood by reference to the accompanying drawings, forming a part of this specification, in which—

Figure 1 is an elevation of one side of a 30 coat embodying my invention in its preferred form; Fig. 2 is a similar view of the garment in its closed condition; Fig. 3 is a similar view illustrating my invention as applied to a "full length coat"; Fig. 4 is a 35 similar view of the same garment in its closed condition; Fig. 5 is a view similar to Fig. 3, showing a slightly modified form of the invention; Fig. 6 is a similar view of the same in a closed condition; Fig. 7 is a 40 view of another modified form of the invention, and Fig. 8 is a fragmentary detail view hereinafter described.

Referring now to the drawings in detail, numeral 11 refers to a lady's coat, which I 45 have shown with the usual front opening when it is provided with the usual buttons 12 and buttonholes 13. In addition to this usual front or other opening, I provide an opening 14 on each side thereof, on a comparatively short garment extending from 50 its lower edge to a point about midway of the sleeve on the under side thereof, as shown in Fig. 1. This opening takes the place of the usual side seam in this location, and the material is cut and finished 55 with such dimensions that provision is made

for the overlapping of the edges 15 and 16 of the opening, the rear edge 15 being preferably arranged to overlap the front edge 16.

On the inside of the rear edge 15, which is shown thrown back in Fig. 1, I provide a series of hooks 17, suitably spaced apart, which are adapted to coöperate in the usual manner with one of a plurality of series of eyelets 18 in the flap 16. I have shown four 60 series of these eyelets in the body portion of the garment, although it will be apparent that more or less than four of such series may be employed if desired. Where this side opening 14 extends into the sleeve of 65 the garment, as shown in Figs. 1 and 3, the four series of eyelets 18 merge into first three then two eyelets and finally one eyelet, whereby the size of the coat may be increased to the greatest extent at points 70 where the greatest increase is most necessary, and to a lesser extent at other points, the adjustment thus being of a character to insure a proper "hang" and a smooth and finished appearance to the garment in any 75 condition of adjustment. In a so-called "full length" coat, I have found that it is unnecessary to have these side openings extend the full length of the garment. As 80 shown in Fig. 3, this opening 14' may terminate slightly below the waist line, and when one of a number of a series of eyelets 18' are engaged by the hooks 17', it will be 85 apparent that the skirt portion 19 of the coat, at the lower end of the side opening, 90 will be folded into a graceful plait 20, the body of the garment at and above the waist line being smooth and close fitting. Similarly, it is not necessary to extend these side 95 openings into the sleeve portions of the garment, as I may terminate these openings at the sleeve, as shown in Figs. 5 and 6. From these figures, it will be apparent that when the hooks 17" are brought into engagement of any one of the series of eyelets 18", a 100 small plait 21 will be formed on the under side of the sleeve at the seam, which will gracefully merge itself into the smooth portion of the sleeve and not detract from the appearance of the garment or the comfort 105 of the wearer.

It will be apparent that when the hooks are brought into engagement with the series of eyelets nearest thereto, one or possibly two of the remaining series of eyelets will 110 be exposed to view. Of course, narrow plaits 22 may be provided to cover each series of

eyelets, as shown in Fig. 8. I prefer, however, to make these eyelets as small as possible and finish them in the same manner as button holes are finished with thread which 5 is of the same color and shade as the material of which the garment is made. In this manner, these eyelets are not noticeable nor can they be seen except upon the closest inspection.

10 In order to insure a more nearly perfect adjustment and "set" of the garment, I much prefer to provide the side openings as shown in Figs. 1, 3 and 5. It will be apparent, however, that these openings are not 15 essential, inasmuch as the material may be folded upon itself, as shown in Fig. 7, where an adjustable plait is illustrated which fully embodies the spirit of my invention. I do not consider that this form of my invention 20 is satisfactory or desirable as the preferred forms shown, but there is no question but what it possesses every feature of adjustability.

It will be understood, of course, that the 25 side of the garment not shown in the drawings is the counterpart of the one illustrated.

With respect to my invention, it will be apparent that I have provided a coat which is, within a certain range, readily adjustable 30 to various sizes and which, when adjusted, presents a neat and finished appearance.

I claim as new and desire to secure by Letters Patent:

1. A coat, jacket or the like provided with 35 the usual fastening means and having an additional opening at each side of the garment, said side openings extending into the under sides of the sleeves and being provided with means for adjustably closing the same.

40 2. A coat, jacket or the like provided with the usual fastening means and having an additional opening at each side of the garment, said side openings extending into the under sides of the sleeves and being provided with means for adjustably closing the 45

same, the range of adjustment being greatest through the body of the garment and tapering to a minimum in the sleeve.

3. A coat, jacket or the like provided with the usual fastening means and having an 50 additional opening at each side of the garment, said side openings extending into the under sides of the sleeves, a plurality of rows of eyelets at one edge and extending the full length of each side opening, and a 55 series of fasteners on the other edge adapted to coöperate with any one of said rows of eyelets to close said opening.

4. A coat, jacket or the like provided with the usual fastening means and having an 60 additional opening at each side of the garment, said side openings extending into the under sides of the sleeves, a row of hooks on the inside of one of the edges of said side opening, a plurality of vertical rows of eyelets in the other edge thereof extending the full length of said opening, said hooks being adapted to coöperate with any one of 65 said rows of eyelets to close said opening in various positions of adjustment. 70

5. A coat, jacket or the like provided with the usual fastening means and having at each side thereof a narrow fold or plait in the body portion which extends into the under side of the sleeve, a plurality of vertical rows of fastening devices in front of 75 said plait and extending throughout the length thereof, and coöoperating fastening devices on the under side of said plait, whereby said plait may be drawn over said 80 body portion and secured to any one of said rows of fastening devices on said body portion to vary the size of the garment.

In testimony of the foregoing, I hereunto set my hand in the presence of two witnesses. 85

WILLIAM PADERNACHT.
